SLURRY DRIER

Adolph G. Carlson, Chicago, Ill.

Application July 15, 1936, Serial No. 90,812

6 Claims. (Cl. 159—9)

The invention relates to slurry driers and has particular reference to apparatus which will make use of the waste heat gases discharged from a cement kiln for drying a slurry of the raw ingredients used in making the cement.

In the wet process of making cement, water is added to the raw ingredients as a more homogeneous mixture is possible with the ingredients in the form of a slurry. After thorough agitation and mixing of the slurry the same is generally passed through drying apparatus to remove most of the water and the dried slurry is then delivered to the kiln. By drying the slurry it is possible to keep the length of the kiln to a minimum as otherwise a longer kiln would be required to provide the necessary drying time for the wet slurry.

An object of the invention, therefore, is to provide improved apparatus for drying a slurry and which will use the waste heat gases expelled from the kiln.

Other objects of the invention are to provide improved drying apparatus of relatively simple construction and which can be economically operated; to provide a drier wherein the slurry will first travel through a heated drum and then in an opposite direction through a heating chamber; and further, to provide improved means for disintegrating and propelling the slurry through the heating chamber to thereby directly subject the same to the drying action of the hot gases passing through the chamber.

With these and various other objects in view, the invention may consist of certain novel features of construction and operation, as will be more fully described and particularly pointed out in the specification, drawings and claims appended hereto.

In the drawings, which illustrate an embodiment of the device, and wherein like reference characters are used to designate like parts;

Figure 1 is a vertical longitudinal view taken substantially through the center of drying apparatus constructed in accordance with the invention;

Figure 2 is a transverse sectional view taken along line 2—2 of Figure 1;

Figure 3 is an expanded view of a section of the drum showing the arrangement of the chains forming the agitating and propelling means for the slurry; and

Figure 4 is a fragmentary sectional view taken along line 4—4 of Figure 1 showing the angular positioning of the scrapers.

The apparatus of the invention is primarily for

drying a slurry of the raw ingredients used in making cement and for illustrative purposes the apparatus is disclosed in connection with a kiln 10. The waste heat gases from the kiln are used by the apparatus for drying the slurry. The kiln is of the conventional type and is provided at its feed end with a housing or enclosure 11 which functions to collect the waste heat gases and deliver a large proportion of the same to the conduit 12 having communication with the housing at the upper portion thereof. Also leading from the enclosure 11 is a stack 13 through which part of the gases are expelled to the atmosphere. The conduit 12 extends upwardly at a slight inclination to the vertical and connects at its upper end with a similar conduit 14 having a downward inclination and which joins at its lower end with the cylindrical casing 15. Said casing provides a heating chamber for the slurry, the waste heat gases after circulating through the chamber being expelled by the outlet conduit 16.

Said cylindrical casing is suitably supported and positioned concentrically with respect to a drum 17. Said drum extends through the casing and projects from each end thereof, the end portions each carrying an annular ring 18 by which the drum is rotatably mounted as the rings contact rollers 20 suitably supported by the concrete foundation 21. Sealing rings 22 are located at each end of the casing to prevent the escape of the gases therefrom while permitting rotation of the drum with respect to the casing. Suitably fastened to the right hand end of the drum is an annular gear 23 having meshing engagement with a worm gear 24 driven by motor 25. The motor may be of the variable speed type and accordingly the drum may be rotated at any speed required for the proper drying of the slurry.

Each end of the drum 17 is closed by a member 26 having a central opening for permitting passage of a tube 27 therethrough, said tube extending axially of the revolving drum and being fixed at each end to a support 28 resting on the foundation 21. Each member 26 is provided with a journal 30 containing packing so as to form an air tight joint between the fixed tube and the rotatable drum. One end of the tube is closed by plate 31 but the other end connects with a slurry feed pipe 32 which delivers slurry to said tube. The slurry is forced longitudinally of the tube and is discharged through opening 33 into the drum 17. Beyond said opening the tube is provided with a partition 34 which blocks the travel

of the slurry, causing complete discharge of the same into the drum. Scrapers 35 are suitably fixed to and depend from the tube 27. Said scrapers are disposed at an inclination, as shown 5 in Figure 4, to cause travel of the slurry longitudinally of the revolving drum.

The opening 33 in the fixed tube 27 admits the slurry to the left end of the revolving drum and openings 36 in the drum deliver the slurry to the 10 right end of the casing 15. The waste heat gases contact the exterior of the drum 17 and thus heat up the cylinder walls of the drum, which in turn have a drying action on the slurry within. The vapor from the slurry, due to the drying of 15 the same, passes out through the openings 36 along with the semi-dried slurry. Located within casing 15 and substantially filling the heating chamber are agitating means for disintegrating the slurry and subjecting the small particles into 20 which the same is divided by said agitating means to the drying action of the waste heat gases circulating through the chamber. The agitating means contemplated by the invention comprises a plurality of chains 37 suitably supported by struts 38 extending radially from the 25 revolving drum 17. The arrangement of the chains and their manner of support is more clearly shown in Figures 2 and 3. In the illustrated embodiment the chains are shown as including 30 five tiers and in each tier the chains extend in six directions from each strut, as will be clear from reference to Figure 3. The struts have an inclination designed to propel the slurry toward the left hand end of the chamber wherein a plurality of scoops 40 are located for causing discharge of the material to the spout 41. Connecting with the end of the spout is a feeder tube 42 having a screw conveyor 43 operating therein. The feeder tube projects within the end of the 40 kiln and the dried slurry is fed at a uniform rate by the screw conveyor to the kiln.

In the operation of the apparatus above described the slurry is forced under pressure through pipe 32 into the fixed tube 27. From the 45 tube the slurry is delivered to the revolving drum and is propelled longitudinally of the drum by reason of the rotation thereof with respect to the scrapers 35. During travel of the slurry through the drum the same is partially dried and in this 50 condition the slurry is discharged from openings 36 to the heating chamber provided by casing 15. The slurry within the casing is kept in constant agitation by the struts and chains which comprise moving elements having the additional 55 function of disintegrating the slurry and directly subjecting minute particles thereof to the drying action of the waste heat gases circulating through the heating chamber. Constant movement of the chains keeps them clean and free of the slurry 60 which would otherwise adhere thereto. The slurry upon reaching the scoops 40 has a substantial portion of the moisture removed therefrom and the dried slurry is fed to the kiln at the proper rate by the screw conveyor 43.

65 The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. In a slurry drier, the combination with means supplying high temperature gases, a casing

receiving gases therefrom, a rotatable drum concentrically arranged with respect to the casing and having a discharge port at one end, a stationary tube extending axially for the length of the drum, scrapers depending from said tube for 5 propelling the slurry within the drum in a direction toward said discharge port, and other means fixed to and rotating with the drum for propelling the slurry through the casing.

2. In a slurry drier, the combination with 10 means supplying high temperature gases, a casing receiving gases therefrom, a rotatable drum concentrically arranged with respect to the casing, means within the drum for propelling the slurry delivered to the drum at one end thereof, said drum having openings at the end opposite the delivery means through which the slurry is discharged into the casing, and means including a plurality of chains rotating with the drum for propelling the slurry through the casing. 20

3. In a slurry drier, the combination with means supplying high temperature gases, a casing receiving gases therefrom, a rotatable drum concentrically arranged with respect to the casing, means within the drum for propelling the 25 slurry delivered to the drum at one end thereof, said drum having openings at the end opposite the delivery means through which the slurry is discharged into the casing, and means fixed to and rotating with the drum for propelling the 30 slurry through the casing, said means comprising struts extending radially from the drum and chains carried by said struts.

4. In a slurry drier, the combination with means supplying high temperature gases, of a 35 casing through which said gases are caused to circulate, a rotatable drum concentric with the casing and having a discharge port at one end, means within the drum for propelling slurry delivered thereto in a direction toward said discharge port, whereby the slurry is discharged from said drum and delivered to said casing, and means rotating within the casing for disintegrating the slurry and subjecting the same to the 40 drying action of said high temperature gases, said means being rotated by said drum.

5. In a slurry drier, the combination with means supplying high temperature gases, of a 45 casing through which said gases are caused to circulate, a rotatable drum concentrically ar- 50 ranged with respect to the casing and having a discharge port at one end, means within the drum for propelling slurry delivered thereto in a direction toward said discharge port, whereby the slurry is discharged from the drum and delivered 55 to said casing, and other means within the casing and rotated by said drum for disintegrating the slurry and subjecting the same to the drying action of the high temperature gases, said other means propelling the slurry within the 60 casing in a direction opposite to the travel of the slurry within the drum.

6. In a slurry drier, the combination with means supplying high temperature gases, a casing receiving gases therefrom, a rotatable drum concentrically arranged with respect to the casing, means delivering slurry to the drum, said drum having openings at its opposite end through which the slurry is discharged into the casing, means within the drum for propelling the slurry toward 70 said discharge openings, and other means fixed to and rotating with the drum for propelling the slurry through the casing.

ADOLPH G. CARLSON.
